[57] CLAIM

The ornamental design for a finger ring, substantially as
shown and described.

DESCRIPTION

FIG. 1 is a front elevational view of a finger ring showing
my new design;

FIG. 2 is a left side elevational view of the finger ring
illustrated in FIG. 1;

FIG. 3 is a rear elevational view of the finger ring illus-
trated in FIG. 1;

FIG. 4 is a right side elevational view of the finger ring
illustrated in FIG. 1;

FIG. 5 is a top plan view of the finger ring illustrated in
FIG. 1; and

FIG. 6 is a bottom elevational view of the finger ring
illustrated in FIG. 1.
